AERIAL BOMB.

1,318,954.

Specification of Letters Patent. Patented Oct. 14, 1919.

Application filed April 18, 1918. Serial No. 229,250.

To all whom it may concern:

Be it known that I, LESTER P. BARLOW, a citizen of the United States, residing at New Haven, in the county of New Haven and State of Connecticut, have invented 5 certain new and useful Improvements in Aerial Bombs, of which the following is a specification.

My invention relates to aerial bombs or the like explosive bodies which are adapted to be dropped or launched from an aeroplane. My invention is applicable to the type of devices disclosed in my application Serial No. 98,737; aerial torpedo, filed May 20, 1916, 10 in which the explosive charge is fired at a fixed distance above the earth or other target by the operation of a firing device carried at the forward end of a pilot or tube which extends forwardly from the casting of the bomb after the same has been launched. In that application means are disclosed whereby the detonator is forced 15 into operative position, and the pilot device or forwardly-extending tube is caused to extend forwardly into its operative position, after an appreciable time interval has elapsed, after the release of the bomb from an aeroplane. In my present invention a different form of means is provided for 20 causing the detonator and forward extrusion to assume their operative positions at the end of a suitable time interval after the bomb has been launched, the present means being exceedingly simple and effective. My 25 invention also comprises a construction of bomb or other like explosive device which may readily be assembled and taken apart, so that the same may be shipped in knocked-down condition. My invention is also applicable to the operation of bombs or other 30 explosive shells or devices different from that described in my previous application referred to, in which it is desirable to cause the detonator to be moved, or other parts 35 to be moved, after the bomb or shell has been started in its flight, in order that the same may arm itself after its flight has started.

Briefly, my invention provides means 40 whereby the detonator and forwardly-extending tube are caused to move by means of air pressure which is released from a container after the bomb has been launched,

the air being caused to pass through a restricted opening into a chamber of fixed 55 dimensions, and thereinto gradually increase in pressure against the detonator, through a time interval, until means retaining the detonator in its inoperative position are overcome, whereupon the detonator is 60 moved by the air into its operative position. The pilot device is at the same time moved by the air. More generally, my device may be referred to as a means for applying 65 pressure by continually increasing amounts to a part which is to be moved, in a bomb or other projectile in flight, until the resistance to movement of the part to be moved has been overcome after an appreciable interval.

In order that a clearer understanding of my invention may be had, attention is hereby directed to the accompanying drawings forming part of this application and illustrating one embodiment of my invention. 70 In the drawings Figure 1 represents a side elevation of an aerial bomb, during its descent, Fig. 2 is an enlarged vertical section through the upper part of the bomb, Fig. 3 is an enlarged vertical section taken through 75 the lower part of the bomb, the forwardly extensible pilot or telescoping tube being shown as carried within the body of the bomb, and Fig. 4 is a horizontal cross-section 80 taken on line 4—4 of Fig. 2.

The bomb illustrated is provided with a magazine or explosive chamber portion, represented generally by the reference character 1, from which the telescoping tube or pilot device, represented generally by the 85 reference character 2, is adapted to be extruded during the descent of the bomb. A stream line portion, represented generally by the reference character 3, extends rearwardly from the explosive chamber section 90 1. The stabilizing vanes 4, 4 are carried by the tubular portion 5 to the rear of the stream line portion 3, and a further tubular portion 6 extends rearwardly from the tubular portion 5.

In bombs of the character described, it is desirable to prevent the bomb from arming itself until it has dropped to a safe distance below the aeroplane from which it is launched. In my device, the detonator accordingly is maintained within the tube 5

81

1,818,954

at a safe distance to the rear of the magazine section 1 until the bomb has dropped a predetermined distance, that is, until a predetermined time interval has elapsed after 5 the dropping of the bomb. The tube 5 referred to may be removably secured to a tube 7 which is a part of the structure of magazine section 1. As shown, the tube 7 extends a short distance to the rear of the rear 10 closure member 8 of the magazine section and is provided at its extreme rear end with screw-threads 9, to which the lower end of the tube 5 may be threaded.

The detonator 10 is normally mounted adjacent 15 the rear end of tube 5 and is supported therein by any convenient means which is adapted to be overcome when sufficient pressure is exerted thereon. Such a connection might be a shearing pin of soft copper 20 or the like securing the detonator to the tube 5, or it might be a device, such as the friction washer 11, which is illustrated as being secured to the rear end of the detonator by the cap 12. The form of detonator 25 illustrated has a substantially solid cylindrical body 13 provided with a peripheral recess, in which the detonating material 14 is supported, this form of detonator being described in my application Serial No. 30 150,712, filed February 24, 1917. This form of detonator, however, is here shown merely for the purpose of illustration and other forms may be used in practising my invention, if desired. The lower end of the detonator 35 is recessed out, as illustrated, and is provided with a cap 15 connected by a passage 16 with the detonating material 14. A tube 17 is secured to the detonator so as to move therewith, by providing the upper end 40 of the tube with screw-threads and screwing the same into corresponding screw-threads formed within the recessed portion at the lower end of the detonator.

The cylindrical member 6 which extends 45 rearwardly from tube 5 is preferably secured thereto by providing tube 6 with an enlarged lower portion 18 having a screw-threaded bore whereby tube 6 may be screw-threaded to the threaded upper portion 19 of tube 5. A container 20 for compressed air or the like is mounted within tube 6. Preferably, container 20 is soldered or otherwise secured to the upper surface of a cylindrical block 21 which is screw-threaded 50 into the lower portion of tube 6 just above the enlargement 18. Block 21 is provided with an opening 22 of small sectional area extending therethrough to connect the space surrounding container 20 with the space 55 above the detonator and below block 21. Container 20 should be sufficiently strong to withstand the pressure of air or other gas contained under a considerable pressure, such, for example, as one thousand pounds 60 per square inch. The container should also

be adapted to contain a sufficient amount of compressed air to perform the operations hereafter to be described.

Tube 6 is provided at its extreme rear end with a right angled tubular extension 23. 70 A plunger 24 is mounted to the rear of the compressed gas container 20 and carries perforating point 25 extending forwardly therefrom and adapted to perforate the container 20 when driven thereagainst with sufficient force. Plunger 24 should be mounted with a sliding fit in tube 6 and may be secured in place by any weak holding means, such as the set screw 26, which may be extended through a suitable screw-threaded 80 opening in tube 6, into engagement with the periphery of plunger 24, to hold the latter in position frictionally.

A cylindrical member, which I may term a cap holder 27, is mounted axially of the extension 23 and carries at its inner end the cap 28. The space immediately to the rear of plunger 24 is filled with any desired explosive material 29, with which cap 28 is connected by the passage 30 extending 85 through cap holder 27. The cap holder preferably is removably mounted in position by providing the same with screw-threads and screwing it into a suitable screw-threaded bore at the upper end of tube 6 until the 90 forward or inner edge of the cap holder comes in contact with the shoulder 31 of the tubular extension 23. The walls of tube 6 are illustrated as thickened to the rear of the normal position of plunger 24 to form a 100 seat 32 against which the rear of the plunger may rest, a gasket 33 preferably being provided to make the seat air-tight.

Firing pin 34 is carried by a plunger 35, 105 slidably mounted in the tubular extension 23, this plunger being pressed toward the cap 28 by a spring 36 which is compressed between the plunger 35 and the screw-cap 37 mounted to close the end of tubular extension 23. Plunger 35 is retained in the position shown by means adapted to be withdrawn when the bomb is launched from an aeroplane. This means is illustrated as a wire 38 shown extending through opposite walls of the tubular extension 23 and the 115 plunger 35 contained therein. Wire 38 is intended to be secured to the aeroplane so that it will be withdrawn from tube 23 and plunger 35 at the moment when the bomb is launched from the aeroplane. This may 120 be accomplished, for example, in the manner described in my application Serial No. 236,915, bombs and discharging means therefor, filed May 27, 1918. For the purposes of my present invention, wire 38 may be secured to the aeroplane in any way, and the bomb launched in any way, which will result in the wire being withdrawn from tube 23 and plunger 35 when the bomb is dropped or launched. Firing pin 34 will thereupon 125 130

strike cap 28 to fire the explosive material 29, which results in breaking the weak binding connection between screw 26 and plunger 24. The latter is accordingly driven violently 5 downward to cause pin 25 to perforate container 20 and release the compressed air therein. The action of the compressed air upon issuing from container 20 is to force plunger 24 rearwardly into engagement 10 with gasket 33 and seat 32 to close the opening at this end. The air thereupon passes through passage 22 in block 21 and gradually increases the pressure in the chamber 39, situated between block 21 and 15 the rear end of the detonator. Pressure will continue to increase in chamber 39 through a period of time, which depends upon the cross-sectional area of passage 22, the size of chamber 39, the pressure of the air within 20 tube 6 and the strength of the frictional supporting means 11 for the detonator. When the pressure in chamber 39 has become sufficient, the resistance of the binding means 11 will be overcome and the detonator forced 25 forwardly in tube 5 into its operative position. The detonator may be given a sliding fit in tube 5.

The detonator may be provided with a passage 40 extending from its upper surface 30 to the interior of tube 17 threaded to the lower end of the detonator. This passage may be of less cross-sectional area than passage 22, and air passes therethrough during the time that pressure is being built up in 35 chamber 39 and while the detonator is being forced downwardly into its operative position.

The construction of the magazine section 1 of the bomb, the forward extrudement or 40 telescoping tubes 2 and means for exploding the detonator when the firing mechanism at the forward end of the tube 2 strikes a target may be the same as was described in my prior application Serial No. 98,737, above 45 referred to. The tube 7, which, as stated, is an extension of tube 5, extends into the magazine chamber 1, which is provided with an outer casing 41, 42, containing the bursting charge of high explosive material 43. 50 A stationary tube 44 extends rearwardly from the forward end of the casing which is provided with a suitable opening in which tube 44 is secured. Tube 44 is provided with an inwardly extending bearing ring 45 having a rearwardly extending portion offset 55 inwardly from tube 44 to provide an annular space in which the lower end of tube 7 is secured, so that tubes 5, 7 and 44 are all fixedly secured together and to the outer casing 60 41, 42. The booster chamber 46 of any desired construction is secured to the rear end of tube 44 and provided with a rear closure member 8 which is secured to casing member 41 to close the rear end of the explosive chamber and to form a cross support for the tubes

44, 7 and 5 and the booster frame. The booster contains a booster charge of high explosive material 47. When the detonator is forced downwardly by the air pressure, as described, the lower edge 48 of the detonator 70 comes into contact with the upper edge of ring 45 when the detonator is in firing position, at which time the detonating material 14 carried by the detonator will be alined with the explosive material 47 in the booster 75 chamber. If desired, a gap may be provided in tube 7 to be alined with the detonating material 14 of the detonator when the latter is in firing position, this gap being closed by a weak closure 49. With the type 80 of detonator illustrated, however, the wall of tube 7 will be shattered and the booster charge 47 detonated when the detonating material 14 is fired, even if the tube 7 is an ordinary steel tube of sufficient strength for 85 the purpose and not provided with any gap such as referred to above.

The tube 17, which is secured at its upper end to the detonator, as stated, has a sliding fit within the bearing ring 45, which, as 90 stated above, is secured to tube 44. A sleeve 50 is secured within tube 17 and is provided on its lower end with an enlargement 51 forming a shoulder against which the forward end of tube 17 abuts. A sliding ring 95 52 is positioned between the inner surface of the fixed tube 44 and the outer surface of tube 17, this ring being adapted to bear against the shoulder formed by the enlargement 51 at the forward end of sleeve 50, the 100 rear surface of ring 52 bearing against the fixed ring 45 when the parts are in the position shown in Fig. 3.

An inner tube 53 is adapted to have a sliding fit inside tube 17, this tube having a ring 54 screw-threaded thereto at its rear end to 105 slidingly engage within tube 17. This tube also has sliding engagement within sleeve 50 and is provided with a peripheral shoulder 55 against which the forward edge of the enlargement 51 of sleeve 50 is adapted to engage. Tube 53 is screw-threaded at its forward end into a suitable axial opening in the cylindrical block 56, which is mounted with a sliding fit in tube 44 adjacent the forward end thereof. A split ring 57 is mounted directly in front of block 56 and the parts are normally held in place by a solid block 58 which is frictionally engaged within the extreme end of tube 44 to close the opening. 115 A stop ring 59 is secured within tube 44 immediately to the rear of block 56.

A rifle cartridge 60, having a bullet 61 extending rearwardly therefrom, both of any ordinary construction, is mounted in the forward end of tube 53, the cap at the forward end of the cartridge being in alinement with a firing pin 62 carried by the sliding member 63 mounted in the axial recess 64 of the block 56, which may be termed 125

the breech block of the mechanism. Sliding member 63 is provided with a forwardly extending stem 65 having a forward enlargement 66 which may be termed the hammer head of the firing mechanism, stem 65 extending forwardly into the split ring 57, and the hammer head 66 being carried in the recess at the forward edge of the split ring 57.

- 10 While the air pressure in chamber 39 is gathering force to press the detonator forwardly, the air which passes through passage 40 in the detonator into the interior of tube 17 exerts pressure on the cartridge 61 to 15 expel the plug 58 at the forward end of tube 44 and the split ring 57, which falls away. The telescoping tubes of the pilot device thereupon move forwardly into the operative position shown in Fig. 1 of the drawings, tube 17 moving forwardly with the detonator until it is stopped by the engagement of the forward edge 48 of the detonator with the rear surface of the stop ring 45. The pressure of the compressed air upon the 20 cartridge 61 will at about the same time cause tube 53, together with block 56, to move forwardly relative to tube 17, until the ring 54 at the end of tube 53 engages the rear edge of sleeve 50, the latter moving forwardly with tube 17, to which it is secured, until the detonator engages ring 45, as stated. Sleeve 52 is stopped by ring 59, through which enlargement 51 passes. When the hammer head 66 strikes the earth 25 or other target, firing pin 62 is driven rearwardly into contact with the cap of cartridge 60, causing bullet 61 to be shot rearwardly through tubes 53 and 17, the bullet striking the cap 15 of the detonator and 30 causing the detonating charge, the booster charge and the main bursting charge 43 of the bomb to be fired successively.

The bomb described is preferably formed in such a manner that the parts may very 45 readily be assembled or taken apart, so that the device may be shipped in knocked-down condition. The stabilizing vanes 4 are preferably secured to the tube 5 to extend radially therefrom by means of removable 50 clamping devices, such as are shown in Fig. 4. The tube 5 may be provided adjacent its upper end with a securing means consisting of a number of metal strips 67, 67, four of these strips being provided, if there are to 55 be four stabilizing vanes, strips 67 having their ends bent radially outward, as shown at 68. Strips 67 may be secured to tube 5 in any desired manner, and together form a ring-like structure with radial openings provided between the adjacent flanges 68. A 60 similar construction is provided at a lower point on tube 5 where the strips 67' are shown as having radially-extending end flanges 68'. The stabilizing vanes 4 are 65 mounted in position by extending their in-

ner edges between the adjacent flanges or lugs 68, 68, and 68' and 68', whereupon screws 69, 69' are extended through suitable openings in the flanges 68, 68', and in the vanes 4.

The stream line section 3 of the bomb referred to comprises a pair of sheet steel members 3¹, 3², bent to shape to form a complete closure for the tubes 5 and 7 between the explosive chamber section 1 and the 75 lower edges of the stabilizing vanes 4. These members are given a circular cross-section which decreases from the forward to the rear ends of the members so as to preserve the stream line form of the bomb. 80 Tube 5 is provided with a fixed collar 70, against the upper edge of which the lower edges of the stabilizing vanes 4 may abut. The casing member 41 of the explosive chamber 1 is offset inwardly adjacent its upper 85 edge to provide a shoulder 71 against which the lower edges of members 3¹, 3² may be seated.

The members 3¹, 3² are mounted in position before the vanes 4 are positioned, members 3¹, 3² being placed in position on shoulder 71 to form a complete closure, after which they may be secured to the explosive chamber section and the tube 5 by any suitable removable means. A convenient means 90 consists of the metal band 72 which may be slipped downwardly over the members 3¹, 3², into position to clamp the same firmly against the upper portion of casing member 41, members 3¹, 3² being of the greatest 95 diameter at this point. Band 72 may be secured in position by providing the same with lugs 73 extending upwardly from the upper edge of the band and providing members 3¹, 3² with slits 74, through which lugs 73 100 may be driven when the band has been placed in position. The upper ends of members 3¹, 3² may be secured in position by flaring the 105 upper ends of the same slightly outwardly, these ends resting in contact with the lower surface of collar 70. A wire 75 may then be passed around members 3¹, 3² below their flaring upper edges and twisted or secured together.

In assembling the devices, it will be noted 115 that the container 20 is secured to block 21 which is separable from tube 6. The cap holder 27 is first positioned in its recess at the upper end of tube 6, after which the explosive material 29 may be placed in its 120 chamber and the plunger 24 put in the position shown in Fig. 2, in which it is secured by set screw 26. Plunger 35 is then slipped into tubular extension 23 of tube 6 and located at the proper point by inserting the 125 end of wire 38 through the aligned openings in tubular member 23 and the plunger 35, or by temporarily extending a pin through the aligned openings. Spring 36 may then be placed in position and compressed by 130

screwing cap 37 on the end of the tubular extension 23. The container 20 is then mounted in position in tube 6 by screwing block 21 in position therein, after which 5 tube 6 may be secured in position on tube 5 by screwing enlargement 18 into position on the end of tube 5, the detonator having previously been mounted in the position shown in the drawings, and the telescoping 10 tubes 2 having been nested in position within the explosive chamber.

It will be noted that my invention is not limited to the exact details of construction described, but that a wide range of equivalents is included as is indicated by the 15 accompanying claims.

What I claim is:—

1. In a bomb, the combination of a body 20 containing an explosive charge, a detonator normally mounted at a distance from said charge, means yieldable under pressure, for holding said detonator in such position, means for guiding said detonator into firing 25 position, a compressed gas container, means adapted to puncture said container, means for operating said last named means, and confining means adapted to cause the gas which issues from said container to increasingly press against said detonator until the 30 same is moved, and to force the same into firing position.

2. In a bomb, the combination of a body containing an explosive charge, a tube leading into proximity to said charge, a detonator 35 mounted in said tube and normally held at a distance from said charge, but movable toward firing position, under the application of sufficient pressure, a closure in said tube having a restricted opening 40 therethrough, a fluid container, and means, operable automatically when the bomb is launched, to cause fluid under pressure to pass from said container through said opening and press upon said detonator, axially 45 of said tube, with a pressure steadily increasing from its first application, until said detonator is moved toward firing position.

3. In a bomb, the combination of a body 50 containing an explosive charge, a tube extending rearwardly from said charge, a detonator mounted therein, normally held at a distance from said charge, but movable toward firing position, under the application of sufficient pressure, said tube having a 55 fixed extension, rearwardly of said detonator, a compressed gas container in said extension, and means, movable into co-operative relation to said container, to cause compressed gas to flow from said container, 60 fill said extension, and press upon said detonator with a steadily increasing pressure, until said detonator is moved toward firing position.

4. In a bomb, the combination of a body 65 containing an explosive charge, means nor-

mally held in inoperative position, and adapted to move into position to arm the bomb, a compressed gas container, means for puncturing the same and means for so confining and directing gas released from 70 the container as to cause it to force said first-named means, after a time interval, into position to arm the bomb.

5. In a bomb, the combination of a body 75 containing an explosive charge, means normally held in inoperative position, and adapted to move into position to arm the bomb, a compressed gas container, means for releasing gas therefrom, comprising a member normally out of relation to said container and movable relatively thereto to cause the release of gas therefrom, and means for thus moving said member, and directing and confining means for causing released gas to force said first-named means, 80 after a time interval, into position to arm the bomb.

6. In a bomb, the combination of a body 85 containing an explosive charge, a pilot device therefor, normally held within the bomb, and adapted to be forwardly extended, a compressed gas container, means for puncturing the same, and directing and confining means for causing gas released from the container to force said pilot device 90 into forwardly extended position.

7. In a bomb, the combination of a body 100 containing an explosive charge, a pilot device therefor, normally held within the bomb, and adapted to be forwardly extended, a compressed gas container, means for releasing gas therefrom, comprising a member normally out of relation to said container and movable relatively thereto to cause the release of gas therefrom, and means for thus 105 moving said member operable when the bomb is launched, and means for so confining and directing released gas as to cause the latter to force said pilot device, after a time interval, into forwardly extended position.

8. In a bomb, the combination of a body 110 containing an explosive charge, a tube extending therein, a pilot device normally contained in said tube and adapted to be forwardly extended after the bomb has been launched, said tube having a fixed rearward extension, a compressed gas container in 115 said extension, means adapted to cause compressed gas to flow from said container so as to fill said extension, and press said pilot device, after a time interval, into its forwardly extended position and means for operating said last named means.

9. In a bomb, the combination of a body 120 containing an explosive charge, means normally held in inoperative position, and adapted to be moved into operative relation to said charge, a compressed gas container, and means for releasing gas therefrom to cause the movement of said first-named 130

- means into operative position, comprising, a tubular member containing said container, a plunger mounted therein for movement toward said container, to release gas therefrom, and normally inactive means for thus moving said plunger, adapted and arranged to be actuated upon the launching of said bomb.
10. In a bomb, having parts adapted to be moved by compressed gas, the combination of a tube, a closed gas container therein, a plunger in said tube, adapted for movement toward said container to release gas therefrom, means for thus moving said plunger, including a spring, and releasable means for holding said spring in compressed, inoperative position.
11. In a bomb, the combination of a tube, having a closure therein with a restricted opening therethrough, a compressed gas container beyond the closure, a plunger beyond the container, adapted for movement to release gas therefrom, and means for thus moving said plunger comprising an explosive charge and firing means therefor.
12. In a bomb, the combination of a body containing an explosive charge, a tube extending rearwardly therefrom, a detonator therein, a tube removably secured to the rear of said first tube, in fixed relation thereto and connecting therewith, a compressed gas container, means in said second tube for causing compressed gas to flow from said container to exert pressure on said detonator to move the same in said first tube, and means carried by said second tube to actuate said first-named means, operable automatically when the bomb is launched.
13. In a bomb, the combination of a tube, a closure member therein adjacent one end, having a restricted opening therethrough, a compressed gas container carried by said member, a plunger normally mounted to the rear of said container, and means to the rear of said plunger, operable to move said plunger to release gas from said container.
14. In a bomb, the combination of a tubular casing containing an explosive chamber,
- a tube extending rearwardly therefrom, of less diameter than said casing, and having a collar thereon, some distance rearwardly from said casing, stabilizing vanes removably secured to said tube, extending rearwardly from said collar, and a casing of diminishing cross-section extending from said first casing into abutment with said collar, said second casing having a plurality of longitudinally separated sections removably secured to said first casing and to said tube.
15. In a bomb, adapted to be dropped from an aircraft, having a part adapted to be moved by compressed gas, the combination of a tube, a closed gas container therein, a plunger in said tube, adapted for movement toward said container to release gas therefrom, means for thus moving said plunger, and means for normally holding said last means inoperative, comprising a removable wire adapted to be secured to an aircraft from which the bomb is to be dropped.
16. In a bomb adapted to be dropped from an aircraft, the combination of a body containing an explosive charge, means normally held in inoperative position and adapted to move into position to arm the bomb, a compressed gas container, means for releasing gas therefrom, comprising a member normally out of relation to said container and movable relatively thereto to cause the release of gas therefrom, means for thus moving said member, means for directing released gas against said first named means, to move it into arming position, and means for normally holding said member-moving means inoperative, comprising a removable wire, adapted to be secured to an aircraft from which the bomb is to be dropped.

This specification signed and witnessed
this 11th day of April, 1918.
